[57] CLAIM

The ornamental design for an exterior surface configuration of an automobile tail light assembly, as shown and described.

DESCRIPTION

FIG. 1 is a rear side view of a right hand side light assembly of an exterior surface configuration of an automobile tail light assembly according to our novel design;

FIG. 2 is a right side view of the assembly of FIG. 1; and, FIG. 3 is a perspective right side view of the assembly of FIG. 1.

The novel design also includes an embodiment of a left hand side light assembly which is mirror symmetrical to the embodiment of FIGS. 1-3 and therefore not separately illustrated.

The dash line showing of adjacent automobile parts is only for showing the surrounding environment and is not part of the claimed design.
